DESIGN FOR A RUBBER ERASER HEAD FOR LEAD PENCILS OR SIMILAR ARTICLES

Herman A. Held, Valley Stream, N. Y., assignor
to Eagle Pencil Company, New York, N. Y., a
corporation of Delaware

Application March 8, 1934, Serial No. 50,980

Term of patent 14 years

To all whom it may concern:

Be it known that I, HERMAN A. HELD, a citizen
of the United States of America, residing at 182
East Mineola Avenue, Valley Stream, New York,
have invented a new, original, and ornamental
Design for a Rubber Eraser Head for Lead Pencils
or Similar Articles, of which the following is a
specification, reference being had to the accom-
panying drawing forming part thereof, in which

Figure 1 is a top plan view of a rubber eraser
head for lead pencils or similar articles showing
my new design, and

Figure 2 is a front view thereof.

I claim:

The ornamental design for a rubber eraser head
for lead pencils or similar articles, as shown.

HERMAN A. HELD.
